UNITED STATES PATENT OFFICE.

OSCAR H. PIEPER AND ALPHONSE F. PIEPER, OF ROCHESTER, NEW YORK.

DENTAL MOTOR.

SPECIFICATION forming part of Letters Patent No. 651,469, dated June 12, 1900.

Application filed March 1, 1900. Serial No. 7,002. (No model.)

To all whom it may concern:

Be it known that we, OSCAR H. PIEPER and ALPHONSE F. PIEPER, of Rochester, New York, have invented certain new and useful Improvements in Dental Motors; and we do hereby declare the following to be a full, clear, and exact description of the same, reference being had to the accompanying drawings, forming a part of this specification, and to the reference-numerals marked thereon.

Our present invention relates to motors, particularly for operating small hand-tools, such as used by dentists, which are manipulated by the operator to grind, drill, or polish and are therefore necessarily capable of universal movement to operate in the most convenient manner; and it has for its object to provide means whereby the motor may be supported in convenient manner and all the necessary movements may be given the tool or handpiece and the latter held within convenient reach of the operator at all times.

To these ends the invention consists in certain improvements and combinations of parts, all as will be hereinafter fully described, the novel features being pointed out in the claims at the end of this specification.

In the drawings, Figure 1 is a perspective view of a motor and connected parts; Fig. 2, a sectional view on the line *a a* of Fig. 1; Fig. 3, a sectional view on the line *b b* of Fig. 2; Fig. 4, a sectional view on the line *c c* of Fig. 5; Fig. 5, a sectional view on the line *d d* of Fig. 4; Fig. 6, a sectional view on the line *e e* of Fig. 4.

Similar reference-numerals in the several figures indicate similar parts.

We have shown our invention as applied to a motor operated by electricity and prefer this by reason of the simplicity and facility of connection and operation, although any other suitable motor could be employed embodying a casing capable of being supported in the same manner.

In devices of this general description it is desirable to support the motor or tool-operating device in such relation to the dental chair that the tool or handpiece may be within convenient reach of the operator and at the same time be normally held out of his way, and we therefore attach the main holding bracket or

support 1 to a stationary support 2, which may be the wall of the room or a standard especially provided for the purpose. This bracket or support 1 preferably embodies a base or plate provided with two horizontally-extending arms 3, in which the motor-frame is journaled to swing laterally on a vertical center. The motor may be of any suitable construction; but we prefer to employ an electric motor, such as shown, the annular frame 4 of which constitutes a magnet composed of plates clamped between rings 17, provided with pole-pieces 15, having coils 16 thereon, and between which rotates an armature 5 on a shaft or arbor 6, journaled in a bearing-yoke 66 at one end and at the other in a bearing in a tubular extension 7, supported meditately on a casing or cover-plate 8. The motor-frame 4 is provided at top and bottom with blocks of non-resonant material, such as soft-rubber blocks or packing-rings 9, secured by headed screws 10, and around the rings are metal bearing-collars 11, adapted to rotate freely in the apertures in the vertically-arranged arms 3, whereby the motor may turn freely on a vertical axis, while the rubber blocks relieve the support from jar and deaden the sound when the motor is in operation. One side of the motor is covered by the hemispherical plate 12, secured by a nut 13 on the armature-arbor yoke 66, a felt washer being interposed between the parts, and a larger washer or packing-ring 14, provided between the larger end of the cover 85 and the annular frame, prevents the entrance of dust and deadens the sound. The side of the motor-frame opposite the yoke is provided with the cover-plate 8, having the tubular extension 7 formed or secured at the center thereof, said plate 8 being secured to the magnet-ring 17 by screws 18 or otherwise. A suitable felt washer 19 is arranged between the edge of the plate 8 and the magnet to exclude dust and deaden the sound. Surrounding the armature-arbor is a bearing-sleeve or bushing 20, secured in the extension 7, which latter is slotted or cored out, the lower sides of the lower slots being inclined toward an oil-cup 23, from which oil or lubricating material is supplied to the bearing by a wick 22, extending into the oil-cup on the lower side of the

extension 7, as shown in Fig. 4. The inclined slots or recesses serve to return to the oil-cup any oil escaping at the ends of the bearing.

24 indicates a split collar adjustably clamped by a screw 25 upon the outer reduced portion of the extension 7 and provided with a flange 26, between which and a collar 27 is arranged a disk 28, formed with or carrying a radius arm or bar 29. The collars 24 and 27 are prevented from movement longitudinally of the extension by a screw 30, passing through the collar 27 and entering an annular groove 31, as shown in Figs. 4 and 5.

32 indicates a belt-pulley on the end of the armature-shaft, from which power is communicated by a belt 33 to the tool 45.

The disk 28, which is, in effect, a part of the radius-arm, turns on a center concentric with the driving-shaft of the motor and is provided with a pin 34, to which is connected one end of a volute spring 35, the other end of the latter being connected to the collar 24 by entering a recess therein, whereby the spring will tend to raise the radius-arm 29 and hold it against the uppermost of a pair of stop-pins 36 on the plate 8, although the arm may be moved downwardly against the tension of the spring when desired. The spring serves to slightly more than counterbalance the radius-arm and connected parts, so as to permit free movement with very slight exertion, but to return the arm to upper position when the tool is released.

37 indicates a bracket hinged at 38 to the upper end of the radius-arm 29 and provided with belt-pulleys 39, over which the belt 33 passes, said pulleys being loose upon an arbor 40, as shown in Fig. 2, and 37 is an arm or rod connected to the bracket, so as to turn axially therein. At the lower end of the arm 37 is provided a loose guide-pulley 41 and also a pivoted handpiece 42, having a guide-pulley and a tool-shaft 43, to one end of which latter a driving-pulley 44 is connected and at the other end a tool 45, as shown. The particular structure of the arm 37, the handpiece, and the connected parts form no part of our present invention, the construction shown being similar to a universally-movable hand-tool now on the market, and these parts may be of any suitable or desired construction, it being sufficient that the driving-belt extending from the pulley 32 to the pulley 44 on the tool-shaft in the handpiece be kept reasonably taut, the tool effectively driven, and a universal adjustment permitted the handpiece. When the handpiece is not in use, the arm 37 is engaged by a hook 46 on an arm 47, adjustably secured to the radius-arm 29, as shown in Fig. 1, out of the way of the operator, but within convenient reach.

The current for operating the motor may be supplied through suitable flexible conductors 50, entering the frame through the cover-plate 8, as shown in Fig. 1, or any other power could be employed in any other manner that

would not prevent the free movements necessary.

The motors, constructed and supported as described, being centrally pivoted occupy but little room, are permitted a free movement on a vertical axis, and the radius-arm 29 and connected parts, while normally supported and held against the stop 36 by the spring, (which latter serves to slightly more than counterbalance the weight of the parts,) can be moved by the manipulation of the handpiece into any position to accomplish the work desired in the most convenient manner, the latter being permitted a universal movement, as will be understood.

We claim as our invention—

1. The combination with the supporting-bracket, the motor-frame pivoted at top and bottom to the bracket to swing in a horizontal plane, and having the tubular extension and the shaft operating in the extension, of the radius-arm movable around the extension, and the spring connected to the extension and arm for elevating the latter.

2. The combination with the motor-casing having the tubular extension at the side, and the rotary shaft operating in the extension, of the radius-arm movable around the extension, and the spring connected to the extension and arm for elevating the latter.

3. The combination with the motor-casing having the tubular extension at the side, and the rotary shaft operating therein, of the sleeve adjustably secured upon the extension, the radius-arm pivoted upon the sleeve, and the spring connected to the sleeve and arm for supporting the latter.

4. The combination with the motor-casing section provided with the tubular extension and the stops, and the rotary shaft operating in the extension, of the sleeve on the extension, the radius-arm thereon operating between the stops, and the spring connected to the sleeve and arm for holding the latter in engagement with the upper stop.

5. The combination with a support, the annular motor-frame having the pivots at top and bottom journaled in the support, and the tubular extension at the side, of the rotary shaft operating in the extension having the belt-pulley, the radius-arm turning on the extension, and the spring for raising said arm.

6. The combination with the supporting-bracket having the perforated arms, of the motor arranged to turn between said arms having the oppositely-arranged flanged blocks of non-resonant material secured thereto and the flanged bearing-collars fitting around the blocks arranged to turn in the perforations in the bracket-arms.

7. The combination with the supporting-bracket having the horizontal arms provided with vertical perforations, of the motor-frame arranged between said arms and provided with the flanged blocks of non-resonant material at top and bottom, the flanged bearing-

collars fitting around the blocks and adapted to turn in the perforations in the bracket-arms and the securing-screws for holding the blocks.

- 5 8. The combination with the supporting bracket having the arms, the annular motor pivoted between the arms to turn in a horizontal plane, said motor having a tubular extension at one side, and a shaft operating 10 therein having a pulley, of the radius-arm pivoted on the extension, the spring for sup-

porting it, the arm connected to the free end of the radius-arm, a handpiece connected thereto, a rotary shaft in the handpiece, a belt extending from the motor-pulley and to the 15 handpiece, and guide-pulleys for the belt.
